[57] **ABSTRACT**

A novel class of heterocyclic spiro compounds is disclosed the members of which possess utility in the therapeutic field, particularly as thymo-analeptics or platelet anti-aggregants. The compounds are derivatives of spiro-[piperidine-4':6-(3,2-a)-thiazolopyrimidine].

SPIRO-[PIPERIDINE-4':6-(3,2-a)-
THIAZOLOPYRIMIDINE]

FIELD OF THE INVENTION

This invention relates to new heterocyclic spiro compounds of utility in the therapeutic field, especially as thymo-analeptics or platelet anti-aggregants.

BACKGROUND OF THE INVENTION

For several years compounds having very varied molecular structures have been proposed for inhibiting the aggregation of blood platelets in human beings. Recently, Elslager (J. of Med. Chem. 1971, page 1759) has described the 5,10-dihydro-3-phenyl-[3,2-b]-thiazolo-2,4-diazepines as being active for this purpose. The activity varies with the nature and position of the substituent on the aromatic nucleus which is in the 3-position of the thiazolodiazepine.

The preparation of the intermediate diamine (o-xylene- ω , ω '-diamine) from the phthalazine is a difficult operation, which can be a serious obstacle to the process being used on an industrial scale.

On the other hand, Sharpe (J. of Med. Chem. 1971, page 977) has described a series of phenacylthio-imidazolines partially cyclised into [2H]-5,6-dihydro-3-hydroxy-3-aryl-[2,1-b]-imidazothiazoles, as being thymo-analeptics.

SUMMARY OF THE INVENTION

It has been found according to the present invention that a new class of compounds consisting of heterocyclic spiro compounds has thymo-analeptic or platelet anti-aggregant activities depending on the nature of the substituents introduced into the heterocyclic nucleus. Another advantage of this class of compounds resides in the low toxicity of the compounds compared to that of the known substances having such activities.

DETAILED DESCRIPTION OF THE INVENTION

The class of compounds with which the present invention is concerned comprises the salts represented by the general formula:

wherein:

R is an alkyl radical having from 4 to 8 carbon atoms or a benzyl radical;

R₁ is a hydroxy radical or a double bond in the 3-2 position of the thiazolo[3,2-a]pyrimidine nucleus;

R₂ is an aromatic radical selected from a phenyl radical preferably substituted by at least one halogen atom or alkoxy radical, a 2-naphthyl radical and a 5,6,7,8-tetrahydro-2-naphthyl radical; and

X is a halogen atom or a pharmaceutically acceptable acid radical, for example an oxalyl radical.

The invention also includes within its scope the free bases of the salts represented by formula I.

5 The compounds of formula I, isolated in the form of salts, can be neutralised and isolated in the form of free bases, which can then be transformed into other salts with an appropriate acid. The compounds of formula I in which R₁ is a double bond in the 3-2 position can be 10 isolated in the form of the free base which can be converted into a salt.

Preferred compounds of the invention are the salts represented by formula I in which R is n-butyl, n-octyl or benzyl and R₂ is 3,4-dichlorophenyl, 2-methoxyphenyl, 2,5-dimethoxyphenyl, 2-naphthyl or 5,6,7,8-tetrahydro-2-naphthyl, and the corresponding free bases of said salts.

Examples of pharmacologically preferred compounds of the invention are the pharmaceutically acceptable salts of the compounds:

spiro[1'-n-butyl-4':6-piperidine-3-(2,5-dimethoxyphenyl)-3-hydroxy-2,3,4,5,6,7-hexahydro[3,2-a]thiazolopyrimidine]

spiro[1'-benzyl-4':6-piperidine-3-hydroxy-3-(2-naphthyl)-2,3,4,5,6,7-hexahydro-[3,2-a]thiazolopyrimidine]

spiro[1'-benzyl-4':6-piperidine-3-(2,5-dimethoxyphenyl)-3-hydroxy-2,3,4,5,6,7-hexahydro-[3,2-a]thiazolopyrimidine]

spiro[1'-benzyl-4':6-piperidine-(3,4-dichlorophenyl)-3-hydroxy-2,3,4,5,6,7-hexahydro-[3,2-a]thiazolopyrimidine]

spiro[1'-benzyl-4':6-piperidine-3-hydroxy-3-(5,6,7,8-tetrahydro-2-naphthyl)-2,3,4,5,6,7-hexahydro-[3,2-a]thiazolopyrimidine],

spiro[1'-n-octyl-4':6-piperidine-3-(3,4-dichlorophenyl)-3-hydroxy-2,3,4,5,6,7-hexahydro[3,2-a]thiazolopyrimidine],

spiro[1'-n-octyl-4':6-piperidine-3-hydroxy-3-(2,5-dimethoxyphenyl)-2,3,4,5,6,7-hexahydro[3,2-a]thiazolopyrimidine],

spiro[1'-benzyl-4':6-piperidine-3-hydroxy-3-(2-methoxyphenyl)-2,3,4,5,6,7-hexahydro-[3,2-a]thiazolopyrimidine], and

spiro[1'-n-octyl-4':6-piperidine-3-hydroxy-3-(2-methoxyphenyl)-2,3,4,5,6,7-hexahydro[3,2-a]thiazolopyrimidine], and the compound:

spiro[1'-n-butyl-4':6-piperidine-3-(2-naphthyl)-4,5,6,7-tetrahydro-[3,2-a]thiazolopyrimidine]

and its pharmaceutically acceptable salts.

The spiro-[4':6-piperidine-3-hydroxy-3-aryl-2,3,4,5,6,7-hexahydro-(3,2-a)thiazolopyrimidines] of the invention, i.e. the compounds of formula I in which R₁ is a hydroxy radical, can be prepared by reacting at

a temperature in the range of from ambient temperature to 50°C. an α -halogenated ketone of the general formula:

wherein Y is a halogen atom, preferably bromine, and R_2 has the same meaning as in formula I, with a spiro compound represented by the general formula:

wherein R has the same meaning as in formula I and Y is a halogen atom, preferably bromine, in an inert solvent, for example ethylene glycol or preferably dimethylformamide.

When the reaction is carried out at a temperature in the range of from 125° to 160°C., preferably 150°-160°C., the spiro[4':6-piperidine-3-aryl-4,5,6,7-tetrahydro(3,2-a)-thiazolopyrimidines] of formula I, in which R_1 represents a double bond in the 3,2-position of the thiazolopyrimidine, are formed.

In the latter reaction, it is preferred to use ethylene glycol as the inert solvent.

The intermediate spiro compounds of formula II, which are the hydrohalic acid salts of spiro[4':5-piperidineperhydro-1,3-pyrimidine-2-thiones] can be prepared by reacting a substituted 4,4-bis-aminomethyl-piperidine represented by the general formula;

wherein R has the same meaning as in formula I, with carbon disulphide and treating the resulting condensation product with a hydrohalic acid to obtain the required compound of formula II.

The compounds of formula III can be prepared by reduction of dinitriles of the general formula:

wherein R has the same meaning as in formula I. The reduction may be effected by catalytic hydrogenation or by the use of a reducing agent such as lithium aluminium hydride.

The dinitriles of formula IV can be prepared by the condensation of a chlorinated base represented by the general formula:

or an acid addition salt thereof, for example a hydrohalic acid salt, wherein R has the same meaning as in formula I, with malononitrile in the presence of an acid acceptor, for example an alkali metal carbonate such as potassium carbonate, and in an aprotic solvent, preferably hexamethyl phosphorotriamide (HMPT).

The various intermediates represented by the foregoing formulae II, III, IV and V form part of the present invention, particularly the intermediates in which R is 10 a butyl, octyl or benzyl radical.

The heterocyclic spiro compounds of formula I will normally be employed as therapeutic agents in the form of a pharmaceutical composition comprising as an essential active ingredient a compound of formula I, in association with at least one pharmaceutical carrier or excipient therefor. The composition will advantageously be a dosage unit form appropriate to the required mode of administration. For example, for oral administration the composition may be in the form of 20 a tablet or capsule.

FIGS. 1-35 of the Drawings illustrate various relevant structural formulae.

EXAMPLES

The following Examples illustrate various embodiments of the invention in a non-limiting manner.

EXAMPLE 1

Spiro[1'-n-butyl-4':6-piperidine-3-(2,5-dimethoxyphenyl)-3-hydroxy-2,3,4,5,6,7-hexahydro-[3,2-a]-thiazolopyrimidine]-dihydrobromide

35 Empirical formula: $\text{C}_{22}\text{H}_{33}\text{Br}_2\text{N}_3\text{OS}$ Molecular weight: 581.42

a. 1-n-Butyl-4,4-bis-cyano-piperidine
Prepared:

i. from bis-(2-chloroethyl)-n-butylamine
ii. from the hydrochloride of the above amine.
40 i. In a fluid-tight and dry reactor, equipped with an agitator, a dropping funnel and a reflux condenser are placed 75.9 g. (0.55 mole) of potassium carbonate and 110 ml. of freshly distilled hexamethyl phosphorotriamide (HMPT); through the dropping funnel is added dropwise and at ambient temperature, and while stirring, a solution of 33 g. (0.5 mole) of malononitrile in 150 ml. of HMPT. The resulting mixture is heated at 60° to 65°C. for 2 hours and then, at the same temperature, are added 99 g. (0.5 mole) of bis-2-chloroethyl)-n-butylamine; the heating is maintained for 3 hours, the HMPT is evaporated under reduced pressure, the solid residue is taken up in water and the solution is extracted with ether; the ethereal layer is washed with water, dried over sodium sulphate, filtered, the ether is evaporated and the residual oil is distilled. In a yield of 45 49% (theoretical yield: 95.7 g.), a colourless liquid having a b.p. 0.25 mm of 82°C. is obtained.
Infra-red Spectrum : nitrile band at 2250 cm^{-1} .

50 ii. In a fluid-tight and dry reactor are placed 182.4 g. (1.32 moles) of potassium carbonate and 240 ml. of freshly distilled HMPT; at ambient temperature and while stirring is added dropwise a solution of 79.2 g. (1.2 moles) of malononitrile in 360 ml. of HMPT. The mixture is heated for 2 hours at 60°-65°C. and then, at 55 this temperature, there are added 91.2 g. (0.66 mole) of potassium carbonate, followed dropwise by a solution of 296 g. (1.2 moles) of bis-(2-chloroethyl)-n-

butylamine hydrochloride in 270 ml. of HMPT. The heating of the mixture at 60°–65°C. is continued for 3 hours and then the HMPT is evaporated under reduced pressure; the residue is taken up in water, extracted with ether, the ethereal layer is washed with water, dried over sodium sulphate, filtered and then the ether is evaporated and the residual oil is distilled. A colourless liquid is obtained. Yield: 104 g. = 45% (theoretical yield: 229 g.) with a b.p. 0.3 mm of 84°–85°C.

The product is analysed in acid oxalate form, $C_{13}H_{19}N_3O_4$; M.W. 281.30.

To a solution of 3.8 g. (0.02 mole) of 1-n-butyl-4,4-bis-cyano-piperidine in 100 ml. of acetone is added dropwise and while stirring a solution of 3.15 g. (0.025 mole) of oxalic acid dihydrate in 50 ml. of acetone. The acid oxalate immediately precipitates and then it is suction-filtered and dried in an oven. Yield: 5.3 g. = 94.5% (theoretical yield: 5.6 g.); m.p. = 173°–175°C., this being unchanged after crystallisation in ethanol.

c. Spiro[1'-n-butyl-4':5-piperidine-1,3-perhydropyrimidine-2-thione]hydrochloride

Empirical formula: $C_{12}H_{24}ClN_3S$ Molecular weight: 277.85

To a solution of 19.3 g. (0.1 mole) of 4,4-bis-aminomethyl-1-n-butyl-piperidine as prepared in (b) in 80 ml. of ethanol are added dropwise, at 60° and 65°C., 8 g. (0.1 mole + 10%) of carbon disulphide, and when the addition is completed, heating takes place on a boiling water bath for one hour, whereafter the mixture is cooled to ambient temperature and there are added thereto 12 ml. of concentrated hydrochloric acid; further heating takes place on the boiling water bath for 6 hours. After heating, the solution is cooled and the formed precipitate is suctionfiltered after adding ether; in a yield of 94.6% (theoretical yield: 27.8 g.), there are obtained 25.6 g. of solid product, m.p. 299°–300°C.

30

Analysis:

	C%	H%	N%	S%	Cl%
Calculated:	51.87	8.70	15.12	11.54	12.77
Found:	51.85	8.67	15.13	11.53	12.80

b. 4,4-bis-aminomethyl-1-n-butyl-piperidine

Prepared by catalytic hydrogenation in the presence of Raney nickel or by reduction with lithium aluminium hydride of the 1-n-butyl-4,4-bis-cyano-piperidine as prepared in (a).

i. Hydrogenation

In a 500 ml. autoclave are placed 48 g. (0.25 mole) of 1-n-butyl-4,4-bis-cyano-piperidine, a solution of 8 g. of NH_3 in 310 ml. of ethanol and 20 g. of Raney nickel. After introducing hydrogen (120 kg/cm²), the resulting mixture is agitated and heated at 60°–70°C. for 2 hours. After heating, the ethanolic solution is filtered, the ethanol is evaporated and the residual oil is distilled. A colourless liquid is obtained which crystallises at ambient temperature. Yield: 28.4 g. = 57% (theoretical yield: 49.8 g.), b.p. 0.9 = 108°–109°C; m.p. = ~25°–30°C.

ii. Reduction by $LiAlH_4$

In a fluid-tight and dry reactor, provided with a reflux condenser, an agitator and a dropping funnel, are placed 3,000 ml. of dry ether and 32 g. (0.84 mole) of $LiAlH_4$; a solution of 54 g. (0.28 mole) of 1-n-butyl-4,4-bis-cyano-piperidine in 300 ml. of ether is added dropwise so as to maintain a gentle reflux. The mixture is then heated under reflux for 4 hours; the mixture is cooled and there are added dropwise 200 ml. of 30% caustic soda solution and 50 ml. of water; the ethereal layer is decanted; there are added thereto the ethereal extracts of the precipitate of formed hydroxides, followed by drying over sodium sulphate and filtering, whereupon the ether is evaporated and the residual oil is distilled. Yield: 90 g. = 80% (theoretical yield: 112 g.). B.P.₁ = 109°–110°C. The product is identified in the form of a trihydrochloride monohydrate:

$C_{11}H_{28}N_3Cl_3$ M.W. = 308.72; m.p. = 219°–221°C.

Analysis:

	C%	H%	N%	S%	Br%
Calculated:	45.44	6.07	7.23	5.51	27.49
Found:	45.46	6.07	7.20	5.58	27.45

Pharmacology

The product shows with the mouse a lethal dose LD_{50} = 1.440 mg./kg. P.O. (per os) and 17 mg./kg. I.V. (intravenous).

Its platelet anti-aggregant effect is determined in vitro in two tests:

a. Aggregation caused by adenosine diphosphate (A.D.P.)

b. Aggregation caused by collagen.

The activity coefficients are expressed by reference to two standards:

a. Phenergan: 10-(2-dimethylaminopropyl)-phenthiazine in the test with adenosine diphosphate (A.D.P.)

b. Acetyl salicylic acid in the test with collagen.

These two standards are arbitrarily assigned the coefficient 1.

The product described in Example 1 has the following coefficients:

a. A.D.P. = 20

b. collagen = 163.

Its thymo-analeptic effect is measured in the antagonism to the ptosis caused by Reserpine (lowering of the bottom eyelid of the animal (mouse) due to the central action of Reserpine). The coefficient 100 is attributed to the control substance Imipramine.

In this test, the product has the coefficient 9. It is not thymo-analeptic, but platelet anti-aggregant.

EXAMPLE 2

Spiro[1'-benzyl-4':6-piperidine-3-hydroxy-3-(2-naphthyl)-2,3,4,5,6,7-hexahydro[3,2-a]-thiazolopyrimidine]dihydrobromide

Empirical formula: $C_{27}H_{31}Br_2N_3OS$ Molecular weight: 605.44

a. 1-benzyl-4,4-bis-cyano-piperidine

In the manner described in Example 1(a), the product is obtained starting with 322.3 g. (1.2 moles) of the hydrochloride of bis-(2-chloroethyl)-benzylamine (m.p. = 147°-148°C.). A colourless liquid is isolated by distillation under reduced pressure, b.p. 0.5 - 0.6 = 123°-126°C. Yield: 181 g. = 66% (theoretical yield: 270 g.). Infra-red μ C N=2250 cm^{-1} .

b. 4,4-bis-aminomethyl-1-benzyl-piperidine

In the manner described in Example 1(b), the product is obtained, starting with 22.05 g. (0.1 mole) of 1-benzyl-4,4-bis-cyano-piperidine as prepared in (a), in liquid form with a b.p. 0.6-0.9 mm = 135°-149°C. Yield: 15.4 g. = 66% (theoretical yield: 23.3 g.). Infra-red γ NH₂ = 3370 cm^{-1} - 3290 cm^{-1}

Analysis: (Results obtained on a twice-distilled sample. b.p. 0.4 = 137°C.)

Calculated: C% 72.06 H% 9.93 N% 18.01
Found: 72.03 9.90 18.05
Trihydrochloride monohydrate
 $C_{14}H_{28}N_3Cl_3O$ M.W. = 360.76

Prepared by the action of hydrochloric acid gas on the above base in solution in ethanol. m.p. = 60 272°-273°C. (after crystallisation in ethanol).

Analysis:

Calculated: C% 46.60 H% 7.82 N% 11.64 Cl% 29.48
Found: 46.60 7.80 11.60 29.50

c. Spiro[1'-benzyl-4':5-piperidine-1,3-perhydropyrimidine-2-thione]hydrobromide

5 Empirical formula: $C_{15}H_{22}BrN_3S$ Molecular weight: 356.33

10 Starting from 4,4-bis-aminomethyl-1-benzylpiperidine as prepared in (b) above, and carrying out the cyclisation in the manner described in Example 1(c) using 40% HBr, there is obtained in a quantitative yield a solid having a melting point of 259°-261°C. (methanol/water).

15

Analysis:

	C%	H%	N%	S%	Br%
Calculated:	50.56	6.23	11.80	9.00	22.44
Found:	50.60	6.26	11.77	8.98	22.42

20 d. To 12.5 g. (0.035 mole) of spiro[1'-benzyl-4':5-piperidine-1,3-perhydropyrimidine-2-thione]hydrobromide as prepared in (c) in suspension in 100 ml. of dimethylformamide are added, at a temperature of from 50°-55°C., 8.7 (0.035 mole) of a ω -bromoacetophenone-2 in 50 ml. of dimethylformamide. After heating for a few minutes, a limpid solution is formed and then a white solid precipitate. After heating for 30 25 minutes at 55°C., filtering with suction, washing with ether and drying, there is obtained in a yield of 89% (theoretical yield: 21.2 g.), 18.9 g. of solid product, m.p. 241°-242°C. After recrystallisation (alcohol/water 3:1), m.p. 254°-256°C.

30

Analysis:

	C%	H%	N%	S%	Br%
Calculated:	53.56	5.16	6.94	5.30	26.40
Found:	53.54	5.19	6.89	5.32	26.45

Pharmacology

LD₅₀ (mouse) = 3200 mg./kg. P.O.

A.D.P. = 10

Collagen = 67

Ptosis to Reserpine = 101

Active dose₅₀ (AD₅₀) = 57 mg./kg.

50 This product is thus at the frontier of the two activities, having a not negligible thymo-analeptic effect and is anti-aggregant in vitro.

EXAMPLE 3

Spiro[1'-benzyl-4':6-piperidine-3-(2,5-dimethoxyphenyl)-3-hydroxy-2,3,4,5,6,7-hexahydro-[3,2-a]-thiazolopyrimidine]-dihydrobromide

55 Empirical formula: $C_{25}H_{33}Br_2N_3O_3S$ Molecular weight: 615.42

The required compound was prepared by the procedure described in Example 2(d) using 2,5-dimethoxy- ω -bromoacetophenone and spiro[1'-benzyl-4':5-piperidine-1,3-perhydropyrimidine-2-thione]hydrobromide as prepared in Example 2(c). Yield = 85%, m.p. 251°-252°C.

After recrystallisation from alcohol/water (6:1), the melting point was unchanged.

Analysis:	C%	H%	N%	S%	Br%
Calculated:	48.78	5.40	6.83	5.21	25.97
Found:	48.75	5.38	6.80	5.19	26.00

Pharmacology

LD₅₀ (mouse) = 1200 mg./kg. P.O. and 41 mg./kg. I.V.

A.D.P. = 27

Collagen = 342

Ptosis to Reserpine = 5.

This product is anti-aggregant, without any thymoanaleptic effect.

EXAMPLE 4.

Spiro[1'-benzyl-4':6-piperidine-(3,4-dichlorophenyl)-3-hydroxy-2,3,4,5,6,7-hexahydro-[3,2-a]-thiazolopyrimidine]-dihydrobromide

Empirical formula: C₂₃H₂₇Br₂Cl₂N₃OS
Molecular weight: 624.28

The required compound was prepared by the procedure described in Example 2(d) starting with 3,4-dichloro- ω -bromo-acetophenone and spiro[1'-benzyl-4':5-piperidine-1,3-perhydropyrimidine-2-thione]hydrobromide as prepared in Example 2(c). Yield = 97%, m.p. = 260°-262°C.

After recrystallisation from water, m.p. was 264°-266°C.

Analysis:	C%	H%	N%	S%	Br%	Cl%
Calculated:	44.25	4.36	6.73	5.14	25.60	11.36
Found:	44.29	4.40	6.75	5.17	25.67	11.40

Pharmacology

LD₅₀ (mouse) = 3200 mg./kg. P.O.

Ptosis to Reserpine = 101

AD₅₀ = 9.5 mg./kg.

EXAMPLE 5

Spiro[1'-benzyl-4':6-piperidine-3-hydroxy-3-(5,6,7,8-tetrahy-

-2-naphthyl)-2,3,4,5,6,7-hexahydro-[3,2-a]-thiazolopyrimidine]-dihydrobromide

Empirical formula: C₂₇H₃₅N₃S Br₂O
Molecular weight: 609.47

The required compound was prepared by the procedure described in Example 2(d) starting from 2- ω -bromoacetyl-5,6,7,8-tetrahydronaphthalene and spiro[1'-benzyl-4':5-piperidine-1,3-perhydropyrimidine-2-thione]hydrobromide as prepared in Example 2(c). Yield = 94%, m.p. 240°-241°C.; after being recrystallised from a mixture of methanol and water (1:5), m.p. = 243°-245°C.

Analysis:

	C%	H%	N%	S%	Br%
Calculated:	53.20	5.79	6.89	5.26	26.23
Found:	53.24	5.81	6.89	5.19	26.20

Pharmacology

LD₅₀ (mouse) = 3200 mg./kg.

Ptosis to Reserpine

AD₅₀ = 26.5 mg./kg.

EXAMPLE 6

Spiro[1'-n-octyl-4':6-piperidine-3-(3,4-dichlorophenyl)-3-hydroxy-2,3,4,5,6,7-hexahydro-[3,2-a]-thiazolopyrimidine]-dihydrobromide

Empirical formula: C₂₄H₃₇Br₂Cl₂OS
Molecular weight: 646.37

a. 1-n-octyl-4,4-bis-cyano-piperidine

In a fluid-tight and dry reactor, flushed with a stream of dry nitrogen, are placed 18.24 g. (0.132 mole) of potassium carbonate and 50 ml. of freshly distilled hexamethyl phosphorotriamide (HMPT); into the resulting suspension is introduced dropwise (in 30 minutes) and at ambient temperature, a solution of 7.8 g. (0.118 mole) of malononitrile in 80 ml. of HMPT. The mixture is then heated between 60° and 65°C. for 2 hours, and thereafter 30 g. (0.118 mole) of bis-(2-chloroethyl)-n-octylamine are introduced at such a speed that the temperature remains between 60° and 65°C., and the heating at this temperature is continued for 3 hours; after heating, the HMPT is distilled off under reduced pressure until there is obtained a viscous residue which is taken up in water and ether; the aqueous layer is once again extracted with ether, the ethereal extracts are copiously washed with water, dried over sodium sulphate, filtered, and then the ether is evaporated and the residual oil is distilled to give the required product, b.p._{0.35} = 117°-119°C. Yield: 23 g. = 79% (theoretical yield = 29.18 g.).

Chromatography in vapour phase on XE 60 (220°C.) in CHCl₃: single product.

Infra-red: μ C N = 2250 cm⁻¹

Found:	72.84	10.16	17.00

b. 4,4-bis-aminomethyl-1-n-octyl-piperidine

In a fluid-tight and dry reactor, flushed with a stream of dry nitrogen, are placed 3000 ml. of anhydrous ether and 25.6 g. (0.675 mole) of lithium aluminium hydride. Introduced dropwise into this suspension (in about one hour) so as to maintain a gentle reflux of the ether is

a solution of 56 g. (0.225 mole) of 1-n-octyl-4,4-bis-cyano-piperidine (prepared as in (a) above) in 250 ml. of ether, whereafter the mixture is heated under reflux for 4 hours; after heating, the aluminium and lithium complex is hydrolysed by adding 260 ml. of 30% caustic soda solution and 100 ml. of water, whereafter the ethereal layer is decanted, washed over sodium sulphate, filtered, and then the ether is evaporated and the residual oil is distilled. A colourless liquid is isolated, which crystallises after standing at ambient temperature, b.p._{1,7} = 175°–176°C. Yield 36.6 g. = 64% (theoretical yield = 57.5). Melting point = 30°C.

Chromatography in vapour phase: on XE 60 (220°C.): single product.

Infra-red: γ NH₂ = 3360 cm⁻¹ to 3270 cm⁻¹.

It is analysed in the form of the trihydrochloride prepared by the action of hydrogen chloride on the above base in solution in ethanol between 0° and 10°C. Very hygroscopic white solid. Melting point = 228°–230°C. (decomposition). (After being dried at 140°C. under reduced pressure).

Analysis: (Results after drying the sample at 100°C. under reduced pressure)

	C%	H%	N%	Cl%
Calculated:	49.38	9.94	11.52	29.16
Found:	49.40	9.92	11.54	29.18

c.

Spiro[1'-n-octyl-4':5-piperidine-1,3-perhydropyrimidine-2-thione]hydrochloride

Empirical formula: C₁₈H₃₂ClN₂S Molecular weight: 333.94

In a fluid-tight and dry reactor is placed a solution of 45 g. (0.176 mole) of 4,4-bis-aminomethyl-1-n-octylpiperidine (prepared as in (b) above) in 150 ml. of ethanol. Into the agitated solution are introduced dropwise over 30 minutes, 13.7 g. (0.18 mole) of carbon disulphide in the following manner: 3 to 4 g. are added at ambient temperature and the remaining part is added between 60° and 65°C. After adding the carbon disulphide, the mixture is heated on a boiling water bath for one hour, whereafter there are added thereto, while cooling so as to keep the temperature at 25°C., 18.5 ml. of 36% hydrochloric acid. Heating then takes place on a boiling water bath for 6 hours, followed by cooling, whereafter the precipitate obtained is suction-filtered, washed with ether and dried at 120°C. under reduced pressure. Melting point = 276°–278°C. Yield: 55.6 g. = 95% (theoretical yield: 58.6 g.).

Analysis: (Results obtained after drying at 110°C. under reduced pressure)

	C%	H%	N%	S%	Cl%
Calculated:	57.54	9.66	12.58	9.60	10.61
Found:	57.50	9.69	12.55	9.60	10.63

The hydrobromide, C₁₈H₃₂BrN₂S - m.w. = 378.42, is prepared by an analogous procedure, replacing the hydrochloric acid by HBr. Yield: quantitative, m.p. (from methanol) 300°–302°C. (with decomposition).

d. To a solution of 9.46 g. (0.025 mole) of spiro[1'-n-octyl-4':5-piperidine-1,3-perhydropyrimidine-thione-2]hydrobromide (prepared as described in (c) above),

in 230 ml. of dimethylformamide, are added at the temperature of 55°C. and over a period of 5 minutes, 6.7 g. (0.025 mole) of 3,4-dichloro- ω -bromoacetophenone in 30 ml. of dimethylformamide, whereafter heating takes place for 30 minutes at 50°C. After evaporation to dryness under vacuum, the white residue is washed with ether. There is obtained, in a yield of 74% (theoretical yield = 16.2 g.), 12 g. of product with a melting point of 225°–227°C. (decomposition). After recrystallisation from methanol/water (3:1), the melting point is unchanged.

15 Analysis:

	C%	H%	N%	S%	Cl%	Br%
Calculated:	44.59	5.77	6.50	4.96	10.97	24.73
Found:	44.60	5.80	6.46	5.00	10.96	24.72

PHARMACOLOGY

LD₅₀ (mouse) = 3200 mg./kg. P.O.

A.D.P. = 22

Collagen = 36

Ptosis to Reserpine AD₅₀ = 21.7 mg./kg.

The low coefficient in the test with collagen indicates that it is a product which is practically deprived of any platelet anti-aggregant effect. On the contrary, the product is thymo-analeptic.

EXAMPLE 7

Spiro[1'-n-butyl-4':6-piperidine-3-(2-naphthyl)-4,5,6,7-tetrahydro-[3,2-a]-thiazolopyrimidine]

Empirical formula: C₂₄H₃₂N₂S Molecular weight: 391.55

To a solution of 22 g. (0.684 mole) of spiro[1'-n-butyl-4':5-piperidine-1,3-perhydropyrimidine-2-thione]hydrobromide (prepared as described in Example 1(c)) in 100 ml. of ethylene glycol is added at 125°C. and while stirring a solution of 17.1 g. (0.0684 mole) of ω -bromoacetophenone-2 in 50 ml. of diethylene glycol dimethyl ether.

After heating the mixture to boiling point for one hour, the volatile products are evaporated under reduced pressure; after dissolving the residual oil in the minimum quantity of isopropanol and adding ether, a hydroscopic, beige solid is isolated, and this is dissolved in 250 ml. of water; the solution is made alkaline by adding 30% caustic solution; it is extracted with ether, dried over sodium sulphate, filtered, evaporated to dryness and a pasty solid is isolated, which crystallises from a dispersion in hexane. Yield = 14.9 g. = 56% (theoretical yield: 26.8 g.); m.p. = 92°–94°C.; after being recrystallised from diisopropyl ether, m.p. = 94°–96°C.

Analysis:

	C%	H%	N%	S%
Calculated:	73.21	7.47	10.73	8.19
Found:	73.65	7.42	10.81	8.24

Acid dioxalate: C₂₈H₃₈N₂SO₈ - m.w. 571.62

Yield: quantitative, m.p. 192°-194°C. (decomposition). After being recrystallised from methanol, m.p. = 193°-195°C. (decomposition).

Acidity index:

Calculated: 384
Found: 380

Analysis:

	C%	H%	N%	S%	O%
Calculated:	58.83	5.82	7.35	5.61	22.31
Found:	58.80	5.85	7.29	5.58	

Pharmacology

LD₅₀ (mouse) = 580 mg./kg. P.O. and 87.5 mg./kg. I.V.
A.D.P. = 10
Collagen = 70
Ptosis to Reserpine = 61.

EXAMPLE 8

Spiro[1'-n-octyl-4':6-piperidine-3-hydroxy-3-(2,5-dimethoxyphenyl)-2,3,4,5,6,7-hexahydro-[3,2-a]-thiazolopyrimidine]-dihydrobromide

Empirical formula: C₂₈H₄₃N₃SBr₂O₃ Molecular weight: 636.72

The required compound was prepared by the procedure described in Example 6, using in step (d) 2,5-dimethoxy- ω -bromoacetophenone in place of the 3,4-dichloro- ω -bromoacetophenone. Yield: quantitative, m.p. = 194°-195°C.; after recrystallisation from ethanol, m.p. = 197°-199°C.

Analysis:

	C%	H%	N%	S%	Br%
Calculated:	49.04	6.80	6.59	5.03	25.10
Found:	49.00	6.84	6.55	5.07	25.17

Pharmacology

LD₅₀ (mouse) = 680 mg./kg. P.O. and 38 ml./kg. I.V.
A.D.P. = 58
Collagen = 923
Ptosis = 33

EXAMPLE 9

Spiro[1'-benzyl-4':6-piperidine-3-hydroxy-3-(2-methoxyphenyl)-2,3,4,5,6,7-hexahydro-[3,2-a]-thiazolopyrimidine]-dihydrobromide

Empirical formula: C₂₄H₃₁N₃SBr₂O₂ Molecular weight: 585.41

The required compound was prepared by the procedure described in Example 2, using in step (d) 2-methoxy- ω -bromoacetophenone in place of the ω -bromoacetonaphthone-2. Yield: quantitative, m.p. = 256°-258°C., unchanged after recrystallisation from a mixture of ethanol and water (1:2).

Analysis:

	C%	H%	N%	S%	Br%
Calculated:	49.23	5.34	7.18	5.48	27.00
Found:	49.25	5.34	7.21	5.51	27.38

Pharmacology

LD₅₀ (mouse) = 380 mg./kg. P.O. and 37 mg./kg. I.V.
A.D.P. = 51
Collagen = 341
Ptosis = 27.

EXAMPLE 10

Spiro[1'-n-octyl-4':6-piperidine-3-hydroxy-3-(2-methoxyphenyl)-2,3,4,5,6,7-hexahydro-[3,2-a]-thiazolopyrimidine]-dihydrobromide

Empirical formula: C₂₅H₄₁N₃SBr₂O₂ Molecular weight: 607.50

25 The required compound was prepared by the procedure described in Example 6, using in step (d) 2-methoxy- ω -bromoacetophenone (obtained by bromination in ether of 2-methoxyacetophenone) in place of the 3,4-dichloro- ω -bromoacetophenone. Yield = 90%, m.p. = 196°-197°C., unchanged after recrystallisation from ethanol.

Analysis:

	C%	H%	N%	S%	Br%
Calculated:	49.42	6.80	6.92	5.28	26.31
Found:	49.38	6.84	6.90	5.26	26.28

Pharmacology

LD₅₀ (mouse) = 900 mg./kg. P.O.

A.D.P. = 22

Collagen = 300

Ptosis = 12

The product is a platelet anti-aggregant.

We claim:

1. A compound selected from the group consisting of pharmaceutically acceptable salts of spiro[1'-n-butyl-4':6-piperidine-3-(2,5-dimethoxyphenyl)-3-hydroxy-3,4,5,6,7-hexahydro-[3,2-a]-thiazolopyrimidine];

pharmaceutically acceptable salts of spiro[1'-benzyl-4':6-piperidine-3-hydroxy-3-hydroxy-3-(2-naphthyl)-2,3,4,5,6,7-hexahydro-[3,2-a]-thiazolopyrimidine];

pharmaceutically acceptable salts of spiro[1'-benzyl-4':6-piperidine-3-(2,5-dimethoxyphenyl)-3-hydroxy-2,3,4,5,6,7-hexahydro-[3,2-a]-thiazolopyrimidine];

pharmaceutically acceptable salts of spiro[1'-benzyl-4':6-piperidine-(3,4-dichlorophenyl)-3-hydroxy-2,3,4,5,6,7-hexahydro-[3,2-a]-thiazolopyrimidine];

pharmaceutically acceptable salts of spiro[1'-benzyl-4':6-piperidine-3-hydroxy-2,3,4,5,6,7-hexahydro-[3,2-a]-thiazolopyrimidine];

pharmaceutically acceptable salts of spiro[1'-benzyl-4':6-piperidine-3-hydroxy-3-(5,6,7,8-tetrahydro-2-naphthyl)-

2,3,4,5,6,7-hexahydro-[3,2-a]-thiazolopyrimidine] 5

pharmaceutically acceptable salts of spiro[1'-n-octyl-4':6-piperidine-3-(3,4-dichlorophenyl)-3-hydroxy-2,3,4,5,6,7-hexahydro-[3,2-a]-thiazolopyrimidine];

Spiro[1'-n-butyl-4':6-piperidine-3-(2-naphthyl)-4,5,6,7-tetrahydro-[3,2-a]thiazolopyrimidine] and pharmaceutically acceptable salts thereof;

pharmaceutically acceptable salts of spiro[1'-n-octyl-4':6-piperidine-3-hydroxy-3-(2,5-dimethoxyphenyl)-

2,3,4,5,6,7-hexahydro-[3,2-a]-thiazolopyrimidine];

pharmaceutically acceptable salts of spiro[1'-benzyl-4':6-piperidine-3-hydroxy-3-(2-methoxyphenyl)-

2,3,4,5,6,7-hexahydro-[3,2-a]-thiazolopyrimidine]; and

pharmaceutically acceptable salts of spiro[1'-n-octyl-4':6-piperidine-3-hydroxy-3-(2-methoxyphenyl)-

2,3,4,5,6,7-hexahydro-[3,2-a]-thiazolopyrimidine].

2. Pharmaceutically acceptable salts of spiro[1'-n-butyl-4':6-piperidine-3-(2,5-dimethoxyphenyl)-3-hydroxy-

2,3,4,5,6,7-hexahydro-[3,2-a]-thiazolopyrimidine].

3. Pharmaceutically acceptable salts of spiro[1'-benzyl-4':6-piperidine-3-hydroxy-3-(2-naphthyl)-

2,3,4,5,6,7-hexahydro-[3,2-a]-thiazolopyrimidine].

30

4. Pharmaceutically acceptable salts of spiro[1'-benzyl-4':6-piperidine-3-(2,5-dimethoxyphenyl)-3-hydroxy-2,3,4,5,6,7-hexahydro-[3,2-a]-thiazolopyrimidine].

5. Pharmaceutically acceptable salts of spiro[1'-benzyl-4':6-piperidine-(3,4-dichlorophenyl)-3-hydroxy-

2,3,4,5,6,7-hexahydro-[3,2-a]-thiazolopyrimidine].

6. Pharmaceutically acceptable salts of spiro[1'-benzyl-4':6-piperidine-3-hydroxy-3-(5,6,7-tetrahydro-2-naphthyl)-2,3,4,5,6,7-hexahydro-[3,2-a]-thiazolopyrimidine].

7. Pharmaceutically acceptable salts of spiro[1'-n-octyl-4':6-piperidine-3-(3,4-dichlorophenyl)-3-hydroxy-

2,3,4,5,6,7-hexahydro-[3,2-a]-thiazolopyrimidine].

8. Spiro[1'-n-butyl-4':6-piperidine-3-(2-naphthyl)-4,5,6,7-tetrahydro-[3,2-a]-thiazolopyrimidine] and pharmaceutically acceptable salts thereof.

9. Pharmaceutically acceptable salts of spiro[1'-n-octyl-4':6-piperidine-3-hydroxy-3-(2,5-dimethoxyphenyl)-

2,3,4,5,6,7-hexahydro-[3,2-a]-thiazolopyrimidine].

10. Pharmaceutically acceptable salts of spiro[1'-benzyl-4':6-piperidine-3-hydroxy-3-(2-methoxyphenyl)-2,3,4,5,6,7-hexahydro-[3,2-a]-thiazolopyrimidine].

11. Pharmaceutically acceptable salts of spiro[1'-n-octyl-4':6-piperidine-3-hydroxy-3-(2-methoxyphenyl)-2,3,4,5,6,7-hexahydro-[3,2-a]-thiazolopyrimidine].
